Patented Sept. 10, 1974

232,696

COMBINED ELECTRIC CAN OPENER AND KNIFE SHARPENER

Ralph David Gourley, Santa Barbara, Calif., assignor to
Rival Manufacturing Company, Kansas City, Mo.

Filed May 26, 1972, Ser. No. 257,469

Term of patent 14 years

Int. Cl. D7—99; D8—05
U.S. Cl. D8—35

Fig. 1.

Fig. 2.

Fig. 3.

Fig. 4.

Fig. 5.

Fig. 6.

FIG. 1 is a rear perspective view of the combined electric can opener and knife sharpener showing my new design;

FIG. 2 is a top plan view thereof;

FIG. 3 is a front elevational view thereof;

FIG. 4 is a side elevational view thereof taken from the right hand side of FIG. 3;

FIG. 5 is a rear elevational view thereof, a portion of the handle cutting lever being omitted for convenience of illustration; and

FIG. 6 is a side elevational view taken from the left side of FIG. 3.

I claim:

The ornamental design for a combined electric can opener and knife sharpener, as shown and described.
